CLAIM

The ornamental design for a laser processing equipment, as shown and described.

DESCRIPTION

FIG. 1 is a front view of a laser processing equipment showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, top and right perspective view thereof; and,

FIG. 8 is a front, bottom and left perspective view thereof. The shade lines in the figures show contour of the article and are not surface ornamentation.
